LOW WATER ALARM

Frank M. Patterson, Pitman, N. J.

Application May 17, 1944, Serial No. 535,964

6 Claims. (Cl. 116—109)

1

The present invention relates to steam pressure equipment and more particularly to a low water alarm for steam boilers and the like.

Some of the objects of the present invention are: to provide an improved apparatus for responding to low water levels of a boiler as an indication thereof, or as a means for assuring prompt regulation of such level; to provide a simple and sure means of protecting a boiler from low water conditions; to provide a device wherein an axially movable shaft is arranged to be shifted under a low water level to operate an alarm; to provide means including a rotating propeller within the boiler or water column for causing an alarm to sound when the boiler level drops to a predetermined low; and to provide other improvements as will hereinafter appear.

In the accompanying drawing, Fig. 1 represents a longitudinal section of a low water alarm embodying one form of the present invention; Fig. 2 represents a sectional detail on line 2—2 of Fig. 1; Fig. 3 represents a section on line 3—3 of Fig. 1; and Fig. 4 represents a side elevation of the device as installed on the water column of a boiler.

Referring to the drawing, one form of the present invention is shown illustratively as used as a low water alarm for boilers, though the invention is not limited to the specific use since it is applicable to feed water regulators, high and low water alarms, steam traps, drainers and other pressure equipment. As shown, the device comprises a body 10 arranged to be attached in leak-proof relation to the side of a water column 11 of a boiler 12, at a point in alinement with the low water level. Bolts 13 secure the body 10 to the column 11 and a gasket 14 is interposed between the parts to make the joint pressure tight. The body 10 has an extension 15 projecting through an opening 16 provided in the column 11, and through which a bore 17 extends axially through the body 10. This bore 17 forms a journal for a shaft 18 passing therethrough and projecting at both ends thereof. This shaft 18 is lubricated and maintained pressure tight by a gland 20 of suitable packing material arranged to be forced into place by a supply duct 21 and feed screw 22. The end of the shaft 18, which enters the column 11, has a screw propeller 23 keyed thereon while the opposite end mounts a turbine 24 and a pair of bell clappers 25, the latter being carried by spring arms 26. The turbine 24 is mounted upon a square section 27 of the shaft 18 to transmit motion to the shaft 18 but the arrangement is such that the shaft 18 can slide axially within

limits provided by the annular box 28 encircling the section 27 and providing the necessary end clearances.

For housing the turbine 24, a closure cap 30 fits about the turbine and has threaded connection with the body 10. This cap 30 also forms a bearing 31 for the end of the shaft and is made pressure tight by a gland 32. Steam is led to one side of the turbine 24 by a port 33 leading from the interior of the column 11, while an exhaust port 34 is provided at the opposite side of the turbine chamber.

For sounding an alarm when the boiler level reaches low water, a bell 35 is mounted upon the cap 30 to be in the path of the clappers 25 when the latter are in alarm position, as will be explained.

For bringing the bell clappers 25 into striking relation to the bell 35, a plunger 36 having a cone shaped end is pressed against the end of the shaft 18 by a coil spring 37 bearing at one end against a collar on the plunger and at the other end against a follower 38 formed as a part of a feed screw 40 threaded through a supporting arm 25 41 and operated by a knurled head 42.

In operation of the device the steam pressure maintains the turbine 24 rotating and as long as the propeller 23 is operating in the water in the boiler it will shift and hold the shaft 18 (to the 30 right as seen in Fig. 1) in a position overcoming the pressure of the spring 37 so that the clappers 25 are removed from the path of the bell 35. When the level of the water falls below the proper low point the propeller is then operating in a steam area and its thrust becomes ineffective to overcome the spring pressure, and the latter then shifts the shaft 18 (to the left as seen in Fig. 1) and the clappers 25 now strike the bell 35 and sound the alarm.

It will now be apparent that a complete unitary low water indicator has been devised wherein a positive and certain indication of a water level is obtained at all times and under all conditions. It should be noted that the propeller operates to maintain the device ineffective as long as the level is above the danger point but when the level falls below such point the propeller being in a steam area can no longer overcome the pressure of the thrust spring whereupon the latter 45 actuates suitable alarm or other mechanism to result in the dangerous condition being corrected. While the turbine is here shown as driven by steam it can, as an alternative, be driven by a small electric motor or other means, as will be 50 understood.

It will be understood that the device of the invention can be applied to any tank or vessel having two mediums therein of different densities which produce different reactions upon the rotatable member of the device. Furthermore, the shaft of the rotatable member can be arranged vertically in the tank or vessel to be vertically adjustable for determining the level of the medium of greater density. In this form a paddle can be used instead of a propeller and the difference in resistance between rotation in the two mediums taken as a measure of the liquid level. By using an electrical circuit an ammeter could indicate the variation in load when passing from one medium to another.

Having thus described my invention, I claim:

1. In a low water alarm for boilers, an indicator, an axially movable shaft entering the boiler at a selected low water level, means for continuously rotating said shaft by fluid pressure within the boiler regardless of level fluctuations, means operated by said shaft when the level falls below said selected low water level for actuating said indicator, and means reacting to the water in the boiler to normally render said indicator operating means ineffective at levels above said low water level.
2. In a low water alarm for boilers, an indicator, an axially movable shaft entering the boiler at a selected low water level, means for continuously rotating said shaft by fluid pressure within the boiler regardless of level fluctuations, means operated by said shaft when the level falls below said selected low water level for actuating said indicator, and means comprising a screw propeller on the shaft in the boiler to normally render said indicator operating means ineffective at levels above said low water level.
3. In a low water alarm for boilers, an indicator, an axially movable shaft entering the boiler at a selected low level, means for continuously rotating said shaft by fluid pressure within the boiler regardless of level fluctuations, a screw propeller on the shaft within the boiler reacting against the water to maintain said shaft in a position corresponding to a safe water level, a spring for moving said shaft to an alarm posi-

tion when said level falls to bring said propeller into the steam space of the boiler, and means operated by said shaft in alarm position to operate said indicator.

5 4. In a low water alarm for boilers, a screw propeller in a vessel subject to boiler pressure, a body attached exteriorly to said vessel, a shaft rotatably and slidably mounted on said body for mounting said propeller, said shaft being moved by the propeller in one direction when immersed in water, a spring for moving said shaft in the opposite direction when the propeller is in the steam space, means for continuously rotating said shaft by fluid pressure within the boiler regardless of level fluctuations, and means operated by the shaft for indicating a low water condition.

10 5. In a low water alarm for boilers, a screw propeller in a vessel subject to boiler pressure, a body attached exteriorly to said vessel, a shaft rotatably and slidably mounted on said body for mounting said propeller, said shaft being axially moved by the propeller in one direction when immersed in water, a spring for moving said shaft in the opposite axial direction when the propeller is in the steam space, means for continuously rotating said shaft by fluid pressure within the boiler regardless of level fluctuations, means operated by the shaft for indicating a low water condition, and means forming pressure tight joints for said shaft and housing.

15 6. In a low water alarm for boilers, an indicator, an axially movable shaft entering the boiler at a selected low level, a turbine keyed on said shaft, means actuated by boiler pressure for continuously operating said turbine to rotate said shaft, a screw propeller on said shaft and within the boiler to react against the water in the boiler to maintain said shaft in a position corresponding to a safe water level, a spring for moving said shaft to an alarm position when said level falls below said selected low level to bring said propeller into the steam space of the boiler, and means operated by said shaft in alarm position to operate said indicator.
